STANLEY BENJAMIN GAMBLE, OF WEST PERTH, WESTERN AUSTRALIA, AUSTRALIA.

BEDSTEAD AND OTHER FURNITURE.

1,405,373.

Specification of Letters Patent. Patented Jan. 31, 1922.

Application filed February 24, 1921. Serial No. 447,515.

To all whom it may concern:

Be it known that I, STANLEY BENJAMIN GAMBLE, of 134 Charles Street, West Perth, Western Australia, Australia, a citizen of the 5 Australian Commonwealth, have invented new and useful Improvements in Bedsteads and other Furniture, of which the following is a specification.

This invention relates to the dovetail fittings, formed of sheet metal, which are frequently used in the joints of bedsteads and other articles of furniture; and the invention has for its object to provide improved fittings of this kind which are particularly applicable for connecting the frame of a spring 15 mattress with the usual wooden bedposts.

According to the invention the socket portion of the dovetail fitting is so mounted on the part whereby it is carried as to be adjustable transversely thereof.

Preferably the plug and the socket portions of the fittings are each formed with a wedge-like protrusion adapted to coact with the face of the other portion to ensure a 25 rigid connection.

The invention will be described with reference to the accompanying drawings of which Figure 1 is an elevation of a socket member, Figure 2 is an elevation of a plug member as used on a wooden side bar, Figure 3 is a sectional elevation of the socket and plug members in engagement. Figures 4 and 5 and Figures 6 and 7, are respectively side and end elevations of a plug member 30 in use (Figures 4 and 5) on angle iron and (Figures 6 and 7) round iron side bars, and Figures 8 and 9 are respectively side and end elevations of a modified form of plug member adapted to be used with a wooden side 35 bar.

The socket member shown in Figures 1 and 3 is attached to a bedpost *a* and comprises two parts, a socket plate *b* and a retaining plate *c*, the former being pressed 40 from a trapezoidal sheet of metal so that the tapering lateral margins *d*, *d* are each bent over to form a groove and a transverse slot *e* is punched intermediately of its length.

The retaining plate *c* is formed from a 45 rectangular metal strip cranked near its ends as at *f* so as to form a flat arch capable of accommodating behind it the length and thickness of the socket plate *b* and punched near one end of said arch to form a wedge-like outward protrusion *g*.

The flat middle portion of the socket plate

b is mounted behind the retaining plate *c*, which is secured in position at each end by screws *h*, *h* and a screw *j* is passed through the retaining plate *c* and the transverse slot 60 *e* in the socket plate *b* to act as an extra support.

The hole in the retaining plate *c* through which the screw *j* passes is punched out to form a countersink for the screw *j* and a 65 projection *k* which engages the slot *e* so as to form a guide therefor.

A plug member for use with the socket member above described is shown in Figures 2 to 7 and comprises a pair of similar 70 superposed bracket plates *l*, *l* having the marginal portions of two similar adjacent sides bent in opposite directions at right angles to the plane of the plates *l*, *l*. One pair of similar sides *m*, *m*, is formed with 75 tapering edges so as to be adapted to engage with the socket member, and each side *m* is punched out near the top as at *n* to form a wedge like outward projection adapted to engage and coact with the surface of the retaining plate *c* to hold the two portions in frictional engagement.

In Figures 2 and 3 the side bar *o* has a vertical longitudinally extending saw cut 80 into which the bracket plates *l*, *l* are slidden so that the tapering marginal portions *m*, *m* are spaced from the end of the bar *o* a distance equal to or greater than the thickness of the margins *d*, *d* of the socket plate *b*, and so that the other pair of bent over marginal portions *p*, *p* of the plug member lie 85 on the upper surface of the bar *o*. The plug member is secured to the bar *o* by means of screws such as *q* passing through the portions *p*, *p*, a bolt *r* passing through the bar *o* 90 and engaging the ends of the portions *p*, *p* and a pin or rivet *s* passing transversely through the bar *o* and the bracket plates *l*, *l*. The method of connecting the plug member to an angle iron side bar *o'* is shewn in Figures 4 and 5 and is similar to that described 95 excepting that no saw-cut is required and the portions *p*, *p* underlie the top of the angle iron *o'* and are secured thereto by means of bolts *t*.

In Figures 6 and 7 the tubular side bar *o* has a longitudinal saw-cut into which the bracket plates *l*, *l* are slidden, and the portions *p*, *p* are bent around and screwed to 100 said tubular bar *o*, a bolt *r* being also provided as in the case of a wooden side bar.

A modified plug member is shewn in Fig-

- ures 8 and 9 and is formed from a flat metal plate u of trapezoidal shape, an extension v at each end being bent over so as to be adapted to engage the upper and lower surfaces 5 of a side bar o . A countersunk hole w is punched in the trapezoidal face u of the plug member so that when mounted on the side bar o , the plate u will be held spaced therefrom by the projection of the countersink w .
- 10 A wedge-like outward protrusion n is also punched in the trapezoidal surface u . The bent over ends v , v are secured to the side bar o by a bolt r passing vertically through the latter.
- 15 Engagement between the plug and socket members is obtained in the usual manner, with the exception that any small variation in the dimensions of the parts to which the respective members of the fitting are attached may be readily compensated for by sliding the socket plate beneath its retaining plate in the requisite direction.
- I claim:—
1. A sheet metal dovetail fitting for connecting together two elements, comprising a socket portion and a plug portion, said socket portion being slidably and automatically adjustable transversely of the element whereon it is mounted after said socket portion has been mounted on said element.
  2. A sheet metal dovetail fitting for connecting a side bar of a bedstead with a bedpost, comprising a socket portion and a plug portion, tapering marginal portions on said socket portion, said marginal portions being bent over and forming oppositely disposed grooves, and means connected with said socket portion for retaining said portion on said bedpost, said means being adapted to give said portion limited transverse movement relatively to said bedpost after said means has been secured to said bedpost.
  3. A sheet metal dovetail fitting for connecting a side bar of a bedstead with a bedpost, comprising a socket portion and a plug portion, bent over tapering marginal portions on said socket portion, said socket portion being apertured transversely intermediate of its length, a rectangular retaining plate, cranked portions on said retaining plate near each end thereof, screws through said retaining plate disposed one at each end thereof and one intermediate 55 of the length thereof, said retaining plate being secured to said bedpost by means of said screws, a portion of said socket portion underlying said retaining plate and adapted to be retained slidably between 60 said plate and said bedpost.
  4. A sheet metal dovetail fitting for connecting a side bar of a bedstead with a bedpost, comprising a socket portion and a plug portion, bent over tapering marginal 65 portions on said socket portion, a flat re-

taining plate, means for securing said retaining plate to said bedpost, said plate being adapted to overlie a part of said socket portion, a resilient wedge-like protrusion on said flat retaining plate, said protrusion being disposed on the outer face and normally lower part of said flat retaining plate.

5. A sheet metal dovetail fitting for connecting a side bar of a bedstead with a bedpost, comprising a socket portion and a plug portion, tapering marginal portions on said plug portion, means for securing said plug portion to the end of said side bar, said means retaining said plug portion parallel with and in spaced relation to the end face of said side bar, a flat surface on said plug member, a resilient wedge-like protrusion on said flat surface, said projection being disposed on the flat outer face and normally upper part of said plug portion.

6. A sheet metal dovetail fitting for connecting a side bar of a bedstead with a bedpost, comprising a socket portion and a plug portion, said plug portion being formed by a pair of bracket plates having similar marginal portions which are bent transversely in opposite directions and form a trapezoidal plate adapted to engage with said socket portion, and means for securing said plug portion to said side bar.

7. A sheet metal dovetail fitting for connecting a side bar of a bedstead with a bedpost, comprising a socket portion and a plug portion, said plug portion being formed by a pair of bracket plates having marginal portions bent transversely in opposite directions and form a trapezoidal plate, and said bracket plates having other marginal portions bent transversely in opposite directions and forming a rectangular plate in a plane at right angles to that of the trapezoidal plate, means for securing said bracket plates to said side bar and means for securing said rectangular plate to said side bar.

8. A sheet metal dovetail fitting for connecting a side bar of a bedstead with a bedpost, comprising a socket portion and a plug portion, said plug portion being formed by a pair of bracket plates having transversely and oppositely bent pairs of marginal portions, screws in one of said pairs of marginal portions and a bolt passing through said pair of bracket plates and said side bar.

9. A sheet metal dovetail fitting for connecting a side bar of a bedstead with a bedpost, comprising a socket portion and a plug portion, said plug portion being formed by a pair of bracket plates, transversely and oppositely bent pairs of marginal portions on said bracket plates, resilient wedge like protrusions on one of said oppositely bent pairs of marginal portions, said protrusions being disposed on the outer face and normally up-

per part of said marginal portions, and means for securing said bracket plates to the end of said side bar.

10. A sheet metal dovetail fitting for connecting the side bar of a bedstead with a bedpost, comprising a socket portion and a plug portion, bent over tapering marginal portions on said socket portion, means connected with said socket portion and adapted to permit limited transverse movement of said socket portion relatively to said bedpost after said means has been secured to said bed post, tapering marginal portions on said plug portion and means for securing said plug portion in spaced parallel relation to the end face of said side bar.

11. A sheet metal dovetail fitting for connecting the side bar of a bedstead with a bedpost, comprising a socket portion and a plug portion, bent over tapering marginal portions on said socket portion, a retaining plate, means for securing said retaining plate to said bedpost, said plate being adapted to overlie a part of said socket portion, tapering marginal portions on said plug portion, means for securing said plug portion in spaced parallel relation to the end face of said side bar, said retaining plate and said plug portion having oppositely disposed faces, resilient protrusions on said faces, the protrusions on one face being adapted to coact with the other face.

12. A sheet metal dovetail fitting for connecting the side bar of a bedstead with a bedpost, comprising a socket portion and a plug portion, bent over tapering marginal portions on said socket portion, a retaining plate, means for securing said retaining plate to said bedpost, said plate being adapted to overlie part of said socket portion, a resilient wedge-like protrusion on said plate, said protrusion being disposed on the outer face and normally lower part of said plate, tapering marginal portions on said plug portions, resilient wedge-like protrusions on said plug portion, said protrusions being disposed on the outer face and normally upper part of said plug portion, transverse extensions disposed one at each end of said plug portion, a bolt passing through said transverse extensions and through said side bar, and means for retaining said plug portion in spaced parallel relation to the end face of said side bar.

13. A sheet metal dovetail fitting for connecting the side bar of a bedstead with a bedpost, comprising a socket portion and a plug portion, bent over tapering marginal portions on said socket portion, a retaining plate, means for securing said retaining plate to said bed post, said retaining plate being adapted to overlie part of said socket portion, said plug portion being formed by a pair of bracket plates having similar marginal portions which are bent transversely in opposite directions and which form a trapezoidal plate, means for securing said plug portion to said side bar, said retaining plate and said trapezoidal plate having oppositely disposed faces, resilient wedge like protrusions on said faces, the protrusions on one face being adapted to coact with the other face.

14. A sheet metal dovetail fitting for connecting a side bar of a bedstead with a bedpost, comprising a socket portion and a plug portion, tapering marginal portions on said socket portion, said marginal portions being bent over and forming oppositely disposed grooves, said socket portion being apertured transversely intermediate of its length, a rectangular retaining plate, cranked portions on said retaining plate near each end thereof, said retaining plate being adapted to overlie that part of said socket portion between said marginal portions, screws passing one through each end of said retaining plate and one through a point intermediate of the length of said plate and through said transverse aperture in said socket portion, a resilient wedge like protrusion on said retaining plate, said protrusion being disposed on the outer face and normally lower portion of said plate, said plug portion being formed by a pair of bracket plates having similar marginal portions which are bent transversely to form a trapezoidal plate, resilient wedge like protrusions on said trapezoidal plate, said protrusions being disposed on the outer face and normally upper part of said trapezoidal plate, other marginal portions on said bracket plates bent transversely in opposite directions and forming a rectangular plate in a plane at right angles to that of said trapezoidal plate; and means for securing said bracket plates and said rectangular plate to said side bar.

STANLEY BENJAMIN GAMBLE.
